UNITED STATES PATENT OFFICE.

EMILY M. NORTON, OF BRIDGEPORT, CONNECTICUT.

IMPROVEMENT IN STEP-LADDERS.

Specification forming part of Letters Patent No. 123,287, dated January 30, 1872.

To all whom it may concern:

Be it known that I, EMILY M. NORTON, of Bridgeport, in the county of Fairfield and State of Connecticut, have invented a new Improvement in Step-Ladders; and I do hereby declare the following, when taken in connection with the accompanying drawing and the letters of reference marked thereon, to be a full, clear, and exact description of the same, and which said drawing constitutes a part of this specification, and represents, in—

Figure 1, a side view; Fig. 2, a sectional view cutting through line $x\ x$, looking down; and in Fig. 3, a vertical section.

This invention relates to an improvement in that class of ladders commonly termed step-ladders; the object being to add to the steps some conveniences not heretofore existing; and it consists in a board top divided into three parts, one of which folds down, and, when up, is supported by swinging brackets beneath, another rising to open a box constructed beneath the step as a receptacle for implements.

A is the ladder, of common construction, except at the upper end it is thrown back, as at B, and to this part the swinging braces C are hinged to spread and support the ladder in the usual manner. Between the sides, at the top, a box, D, is constructed, and on the top a stationary piece, E, is fixed, and to this a cover, F, for the box is hinged, as seen in Fig. 3, and

upon the back side of the fixed piece E an extension, G, is hinged, to fold down, as in Fig. 1, or up to extend, as in Fig. 3. Beneath the fixed piece E are hinged two swinging brackets, H H, which, when not required for use, fold back beneath the fixed piece E, as denoted in broken lines, Fig. 2.

When the extension G is required for use, raise the said part G and turn the brackets out, as denoted in Figs. 2 and 3. The broad shelf at the top, when not required for use, folds in such a manner as to be out of the way, and adds to the step a great convenience in many cases when a person necessarily requires several articles for use, the box D forming a receptacle for many such articles, and which, were it not for the extension G, would be of little use, because the broad top is required to lay articles thereon, which, without the extension, would be reduced by the width of the opening cover.

I claim as my invention—

In a step-ladder, consisting of the ladder A with its extended top B and support C, the box D, fixed top E, swinging cover F, and hinged part G supported by the swinging brackets H H, substantially as set forth.

EMILY M. NORTON.
